NEW JERSEY.

POWDER AND ROUGE CONTAINER.

1,363,218.

Specification of Letters Patent. Patented Dec. 28, 1920.

Application filed September 10, 1920. Serial No. 409,457.

To all whom it may concern:

Be it known that we, ROBERT Y. BARROWS and GEORGE H. HARMAN, citizens of the United States, residing at Rutherford, in the 5 county of Bergen and State of New Jersey, and residing at Glen Ridge, county of Essex, and State of New Jersey, respectively, have invented certain new and useful Improvements in Powder and Rouge Containers; 10 and we do hereby declare the following to be a full, clear, and exact description of the invention, such as will enable others skilled in the art to which it appertains to make and use the same, reference being had to the accompanying drawings, and to characters of 15 reference marked thereon, which form a part of this specification.

The present invention relates, generally, to improvements in cases or boxes adapted to 20 contain face-powder and rouge compacts; and, the invention has reference, more particularly, to a novel construction of double compartment case or box in combination with a novel coöperating puff-member.

25 The invention has for its principal object to provide an attractive, convenient and simple construction of combination double compartment case and coöperating puff-member; the same comprising a pair of 30 shells or body-members hinged together so as to mutually close one upon the other, each shell or body member providing a compartment adapted to hold a compact, and being further provided with means for retaining 35 the compacts in place, there being combined in novel relation to said case a removable puff-member, which serves, in addition to its ordinary functions, as a partition between the compacts when the box or case is 40 closed, and which possesses a finger-piece adapted to project exteriorly of the box or case, when the latter is closed, to also serve as a means for suspending the box or case from a chain, or other desired form of carrying means.

45 Other objects of the present invention, not at this time more particularly enumerated, will be clearly understood from the following detailed description of the same.

50 With the various objects of the invention in view, the same consists, primarily, in the novel combined double compartment case and puff-member hereinafter set forth; and, the invention consists, furthermore, in the 55 novel arrangements and combinations of the

various devices and parts, as well as in the details of the construction of said parts, all of which will be more fully described in the following specification, and then finally embodied in the claims appended thereto.

60

The invention is clearly illustrated in the accompanying drawings, in which:—

Figure 1 is a face elevation of the novel combined case and puff-member in closed condition, made according to and embodying 65 the principles of the present invention; Fig. 2 is an edge elevation of the same; Fig. 3 is a vertical section through the same, taken on line 3—3 in said Fig. 1; Fig. 4 is a face view of the case in open condition, 70 with the puff member removed for use; Fig. 5 is a detail vertical section of the puff-member alone, taken on line 5—5 in said Fig. 4; and Fig. 6 is a face view of a somewhat modified construction of puff-member. 75

Similar characters of reference are employed in all of the hereinabove described views, to indicate corresponding parts.

Referring now to said drawings, the reference-character 1 indicates the complete 80 novel double compartment case and puff member made according to and embodying the principles of the present invention, the same comprising a shell or body member 2 and a second shell or body member 3, the 85 former providing a compact holding compartment 4, and the latter providing a similar compact holding compartment 5. Said respective shells or body members 2 and 3 may be made in any desired form of exterior shape or contour, to provide, when closed together, the desired ornamental effect and appearance.

Said shell or body member 2 is provided 95 at its open periphery or mouth with an inwardly off-set cover engaging bezel 6, which telescopes into the open end of said shell or body member 3, when the shells or body members are mutually closed one upon the other, thus preventing lateral displacement 100 or separation of said parts when thus closed.

The said shells or body members 2 and 3 are mutually pivoted together, to swing apart one from the other, by means of a hinge member 7, suitably secured to the adjoining sides thereof. The bezel 6 of said shell or body member 2 is provided, at a point diametrically opposite the hinge connection, with an outwardly pressed catch nosing 8, and, in like manner, the marginal 110

portion of the side wall of said shell or body member 3 is provided with a correspondingly located catch receiving member 9, which snaps over said catch nosing 8 when 5 said shells or body members are closed together, to thereby hold the same in their mutually closed relation.

One shell or body member, for example the shell 3, has its face wall cut away to 10 provide an opening 10 surrounded by a flange or marginal bezel 11, against the inner side of which is seated a mirror 12, so that the face of the same is exposed through said opening 10. Said mirror 12 is retained in 15 operative position by means of a suitable inlay plate 13 secured within the bottom of said shell 3 behind said mirror.

One shell or body member, for example the shell 2, is adapted to hold seated within 20 its compartment 4, a compact 14 comprised of white face-powder, and the other shell or body member, for example the shell 3, is adapted to hold seated within its compartment 5, a compact 15 comprised of rouge 25 or the like. Each shell or body member is provided in its side walls, and suitably located with reference to the size and thickness of the compacts, with an annular outwardly pressed member 16 providing a 30 groove for seating and holding a spring retaining ring 17 adapted to engage the edges of the respective compacts to thereby retain the latter against accidental displacement from proper seated relation within said 35 compartments. While such form of compact retaining means is convenient, we do not necessarily limit ourselves to the same specifically, since various forms and arrangements of mechanical means for such 40 purpose may be employed with equal success.

Combined with the novel double compartment case, thus above described in detail, is a novel construction of puff-member, removably associated with the case in a novel manner so as to serve, in addition to its functions as a means for applying powder or rouge to the person of the user, certain purposes in combination with the case, as is about to be disclosed. Primarily said novel puff-member comprises a double faced puff-body 18, having means for flexibly stiffening the same, and a novel arrangement of finger piece 19 projecting outwardly from its edge. 55 When said puff-member is operatively associated with the case, and the latter is closed, the puff-body 18 will lie intermediate the faces of the compacts 14 and 15, with one of its faces adapted to be engaged operatively 60 with one compact, and its other face adapted to be engaged operatively with the other compact, and in such position the puff-body 18 provides a partition-like member between the compacts. When thus arranged the 65 finger-piece 19 projects exteriorly from the

side walls of the case shells; the side wall of the shell 2 is provided at its free edge with a suitably located cut out portion or notch 20 embracing said finger-piece 19 from one side, while the side wall of the shell 3 is provided at its free edge with a correspondingly located cut out portion or notch 21 embracing said finger-piece 19 from the opposite side, thus permitting said finger-piece 19 to project outwardly from the 70 closed case. The outer extremity of said finger-piece 19 is preferably provided with an enlarged portion 22 having a perforation or opening 23, so that a suspending cord, chain or the like 24 may be attached thereto. 80 It will thus be apparent that when the case is closed with the puff-member in proper association therewith, the same may be readily suspended for carrying by the exteriorly projected end of the finger-piece 19, thus 85 affording a very compact, neat and attractive combined case and puff for the purposes set forth.

In its detail construction the puff-member involves certain novel structural features, which combine to render the same admirably adapted for the several purposes served thereby in the combined case and puff. In the first place, since the puff-member is designed to be used with both the white 95 powder compact and the red or tinted rouge compact, it must be provided with two operative faces, the one face serving for the powder and the opposite face for the rouge, and at the same time while it is highly desirable that the puff-body 18 be stiff enough to retain its generally flat disk-like shape, it must, nevertheless be rendered sufficiently flexible to readily permit the same, when grasped by the finger-piece 19, to yield or 100 flex so that the desired operative face may be caused to engage the skin of the user 105 with ease. To this end the puff-body 18 is comprised of two disk-like members, made of velour, or any other suitable fabric or 110 material, the same being sewn together at their peripheries, so as to provide an interior pocket. Inclosed within the interior pocket, thus provided is a thin sheet of resiliently flexible material 25, such, for example, as thin sheet metal of desired temper. This sheet 25 serves not only to retain the puff-body in normal flat disk-like shape, but renders the same flexible in use, while readily returning to normal flat form when use 115 is discontinued. The finger-piece 19, is preferably made of a metal body doubled upon itself to provide a pair of opposed jaws 26, having inwardly projecting teeth 27 around their edges. The puff-body 18, formed as 120 above described is inserted to extend partially between said jaws 26, the latter then being forced together to cause the teeth 27 to engage in the puff-body 18, and firmly grip the same. The jaws 26 are held in the 125 130

described puff-body gripping position by a rivet 28 which securely holds the two parts of the finger-piece together.

The functions desired of the puff-body 5 may also be obtained by the construction illustrated in Fig. 6 of the drawings, in which the detail structure is somewhat modified. In this form the double faced puff-body 18 providing an interior pocket, is 10 provided with a finger-piece 29 having an inner tongue 30, which is inserted within the pocket. Connected with said tongue is a flexible hoop 31, preferably made of spirally coiled wire, the ends of which are engaged 15 and secured to said tongue 30, at a point adjacent to the exteriorly projecting portion of the finger-piece 29, by means of anchor lugs 32, which are integrally formed in connection with said tongue 30, and which are 20 turned over and clenched about the ends of said hoop to anchor the same to the finger-piece. In this construction the hoop tends to hold the puff-body to its normal flat disk-like shape, while readily permitting the free 25 edge of the same to flex when in use.

We are aware that some changes may be made in the general arrangements and combinations of the several devices and parts, as well as in the details of the construction 30 thereof, without departing from the scope of the invention as set forth in the foregoing specification, and as defined in the appended claims. Hence, we do not limit our invention to the exact arrangements and 35 combinations of the said devices and parts as described in said specification, nor do we confine ourselves to the exact details of the construction of said parts as illustrated in the accompanying drawings.

40 We claim:—

1. A double compartment case comprising a pair of body members each providing a compact-receiving compartment, the same being hinged together to close one upon the 45 other, a puff-member adapted to be inclosed within said case intermediate the compartments formed by said body members, said puff-member having a finger-piece extending outwardly from the periphery thereof, and 50 the meeting edges of said body members having opposed notches forming an opening permitting the exterior projection of said finger-piece when said body members are closed together.

55 2. A double compartment case comprising a pair of body members each providing a compact-receiving compartment, a hinge means pivotally interconnecting said body members so that the same may be mutually 60 closed one upon the other, a removable double-faced puff-member inclosed within said case to lie between and separate the compartments seated respectively in said compartments, a finger-piece connected with said 65 puff-member to project outwardly from the

periphery thereof, and the meeting edges of said body members having opposed notches embracing said finger-piece to permit the latter to project exteriorly from the case when the body members are closed together. 70

3. A double compartment case comprising a pair of opposed and pivotally interconnected body members adapted to close one upon the other, each body member providing a compact receiving compartment, means connected with each body member for holding a compact in the compartment formed thereby, a removable double faced puff-member normally disposed between said compartments and the compacts therein, said puff 75 member having a finger-piece extending outwardly from its periphery, and the meeting edges of said body-members having opposed notches embracing said finger-piece to permit the latter to project exteriorly from the 80 case when the body members are closed together. 85

4. A double compartment case comprising a pair of opposed and pivotally interconnected body members adapted to be closed 90 one upon the other, each body member providing a compact receiving compartment, means connected with each body member for holding a compact in the compartment formed thereby, a removable double faced 95 puff-member normally disposed between said compartments and the compacts therein, said puff member having a finger-piece extending outwardly from its periphery, means embedded in said puff-member to render the 100 same resiliently flexible, and the meeting edges of said body-members having opposed notches embracing said finger-piece to permit the latter to project exteriorly from the 105 case when the body members are closed together.

5. A double compartment case comprising a pair of opposed and pivotally interconnected body members adapted to close one upon the other, each body member providing a compact receiving compartment, a removable double faced puff-member normally disposed between said compartments and the compacts thereof, said puff-member having a finger-piece extending outwardly from its 110 periphery, the meeting edges of said body members having opposed notches embracing said finger-piece to permit the latter to project exteriorly from the case when the body members are closed together, and said exteriorly projecting end of said finger-piece having a perforate portion for the attachment of a case suspension and carrying means thereto. 115

6. A double compartment case comprising 120 a pair of opposed and pivotally interconnected body members adapted to close one upon the other, each body member providing a compact receiving compartment, one of said body members having an opening in 130

its outer wall, a mirror associated with said latter body member with its reflecting surface exposed through said opening, means for retaining said mirror in place, a removable double faced puff member normally disposed between said compartments and the compacts thereof, said puff-member having a finger-piece extending outwardly from its periphery, and the meeting edges of said body members having opposed notches embracing said finger-piece to permit the latter to project exteriorly from the case when the body members are closed together.

7. A double compartment case comprising a pair of opposed and pivotally interconnected body members adapted to close one upon the other, each body member providing a compact receiving compartment, one of said body members having an opening in its outer wall, a mirror associated with said latter body member with its reflecting surface exposed through said opening, means for retaining said mirror in place, a removable double faced puff member normally disposed between said compartments and the compacts thereof, said puff-member having a finger-piece extending outwardly from its periphery, the meeting edges of said body members having opposed notches embracing said finger-piece to permit the latter to project exteriorly from the case when the body members are closed together, means embedded in said puff member to render the same resiliently flexible, and said exteriorly projecting end of said finger-piece having a perforate portion for the attachment of a case suspension and carrying means thereto.

8. As a sub-combination, a double faced puff member, means embedded within said puff member to render the same resiliently flexible, and a finger-piece projecting outwardly from the periphery of said puff member.

9. As a sub-combination, a double faced puff-member, means embedded within said puff member to render the same resiliently flexible, a finger-piece comprising a body doubled upon itself to provide a pair of opposed gripping jaws between which the puff member is engaged to permit said finger-piece to project outwardly from the periphery of said puff member, and means for securing said jaws in gripping position.

10. As a sub-combination, a double faced puff member, means embedded within said puff member to render the same resiliently flexible, a finger-piece comprising a body doubled upon itself to provide a pair of opposed gripping jaws between which the puff member is engaged to permit said finger-piece to project outwardly from the periphery of said puff member, and means for securing said jaws in gripping position, said jaws having a plurality of inwardly projecting teeth disposed around their edges.

In testimony that we claim the invention set forth above we have hereunto set our hands this 30th day of August, 1920.
